UNITED STATES PATENT OFFICE.

ERIC H. RADFORD, OF LOS ANGELES, CALIFORNIA.

BUCKET.

Application filed September 27, 1922. Serial No. 590,965.

My invention particularly relates to a bucket which is especially adapted for use in connection with the delivery of granular substances such as crushed ice, salt and the like. As these substances tend to adhere to the walls of the bucket or partially solidify therein, it sometimes becomes necessary in order to dislodge the contents of a bucket to use force by inverting and bumping the top edge of the bucket against a solid body or by pounding on the side walls and bottom of the bucket. It is therefore essential that buckets of this character be so constructed as to not readily become distorted when subjected to such usage.

It is the principal object of my invention to provide a bucket which is so constructed that it will hold up and withstand hard usage.

Another object is to provide the portions of the body of a bucket where excessive wear occurs with such reinforcing that the bucket may be subjected to considerable wear without the bucket becoming useless.

With the foregoing and other objects in view, my invention consists in certain novel features of construction hereinafter described and claimed and illustrated in the accompanying drawings, in which:

Figure 1 is a plan view of the bucket.

Figure 2 is a view in side elevation with parts broken away and shown in section.

Figure 3 is an enlarged fragmentary view in vertical cross section, as seen on the same plane as the sectional portion of Figure 2.

Referring to the drawing more specifically, the curved conical shaped portions 4 and 5 form the side walls of the bucket that are joined together by double seaming 6 and 7.

The conical side walls 4 and 5 are extended into cylindrical end portions at the top and bottom; the upper end portion being drawn to a smaller diameter than the projected cone to provide an annular wall 8 around the exterior of which is placed a flat thick band of iron 9 that is secured to the wall by rivets 10.

The upper edge of each portion 4 and 5 is bent outwardly and downwardly over the upper edge of the band 9 forming a flange 11 which extends over the outer periphery of the band.

The bottom edge of the conical side walls 5 is spread to form an annular wall 12 extending from an inwardly curved beaded por-

tion 13 at the lower termination of the conical walls 4 and 5.

A bottom 14 is constructed by placing an inverted dish-shaped circular disc 15 on an annular band of iron 16 being fixed to the band by welding 17 around the edge thereof and on the top of the band thus forming an inverted cup-shaped bottom 14 for the bucket. The bottom is forcibly inserted into the lower end of the wall 12 until the lower edge of the band 9 is even with the edge of the straight wall 12. The edges are then welded together to form one integral bottom edge 18.

The inwardly curved beaded portion 13 unites the lower edge of the side wall of the bucket with the annular wall 13 in a very stable manner and yet produces a slight resiliency in the bottom portion of the bucket which provides for a tighter fit when the bottom band 16 is forced into place. The convexity of the bottom disk 15 also contributes to this result.

The seams 6 and 7 run almost to the external band 9 around the wall 8 and to the internal band 16 within the wall 12.

Ears 19 and 20 are welded opposite each other on the outside of the band 9 which ears have perforated ends 21 and 22 projecting above the top edge of the bucket for the reception of a bail 23 provided with outwardly turned ends 24 and 25 that hook into the ears 19 and 20. The bail 23 is provided with a loose sleeve 26 serving as a hand hold, there being kinks 27 formed thereon to fix it in the middle of the bail. The bucket is galvanized in the usual way when completed.

The purpose of the bent-over flange 11 of side walls 8 on the upper edge is so that the walls will be held against the band 9 when the edge is bumped against a solid object and also this flange is placed in opposition to the rivets 10 so as to firmly hold the band 9 on the walls 8 and prevent the wall from being bent inwardly.

The welded bottom edge 18 is to securely hold the side wall 12 to band 16, to prevent the wall from being torn away and to provide a thick edge to take excessive wear at this point.

I claim:

In a bucket, a side wall formed with an annular wall at its lower end, an annular metallic reinforcing band, an inverted dish-shaped disc welded throughout its periphery

to the upper edge of said band; said band being arranged within said annular wall with its outer periphery in close contact with the inner periphery of said wall and with the lower edge of said band extending flush with the lower end of said wall; said band being of greater thickness and of heavier material than that of the bucket side wall and of the disk carried thereby; said band and wall being joined together by a weld joint extending along their contiguous lower end margins, there being an inwardly curved beaded portion around the bucket which unites the lower edge of its side wall to the recited annular wall.

ERIC H. RADFORD.
